UNITED STATES PATENT OFFICE.

LUDOVIC JULES MARIUS PLANTIER, OF ANNONAY, ARDECHE, FRANCE.

DILATOR AND THE LIKE.

Application filed May 4, 1921. Serial No. 466,629.

To all whom it may concern:

Be it known that I, LUDOVIC JULES MARIUS PLANTIER, a citizen of the French Republic, residing at 19 Boulevard de la République, 5 Annonay, Ardeche, France, have invented certain new and useful Improvements in Dilators and the like, of which the following is a specification.

This invention comprises improvements in 10 dilators and the like, these being surgical instruments for expanding organic ducts. Instruments actually employed in surgery for the dilation of the natural ducts (as for example, the wind pipe, urinary duct, and so 15 on) which have been affected by contraction or spasm are in the nature of probes, olives, air bags, and so on. All these act directly upon the mucus, against which they are immediately applied, and exercise upon 20 it a pressure or friction which is quite harsh and damaging and which, moreover, often stretches or elongates the organ in an unfortunate manner. In some cases this friction causes an abrasion of the usually fragile 25 epithelium protector and sets up hemorrhage, or creates fissures or erosions which may preserve the spasm, or produces infection or causes wounds which leave scars behind.

30 In the case of some of them, where several olives are used in succession, the second being larger than the first and so on, the second olive may take a wrong course and come to a stop blindly in a cul-de-sac, in 35 spite of the fact that the first olive, which can better be directed on account of its lesser dimensions, has taken the correct course.

Bougies or catheters on account of the uniformity of their diameters are the cause 40 of needless pain throughout the course of their passage in the wind pipe and they prevent swallowing of the saliva as well as occasionally rendering respiration difficult and setting up cyanosis. Locally expandible 45 metallic dilators imprison the mucus in the spaces between their sides and have a nipping effect. As regards pneumatic dilators, apart from their volume, these are objectionable owing to the fact that they themselves suffer strangulation and constriction 50 at the place of contraction of the natural duct where they are subjected to the greatest pressure, whereas they should, on the contrary, offer at this place their largest possible diameter.

A lengthy experience of the inadequacy

and even of the danger of these different recognized means is responsible for bringing about the invention of the present improvements. In order to enable the invention to 60 be readily understood, reference is made to the accompanying drawing, attached to and forming part of this specification, in which:—

Figure 1 is a vertical section of a dilator 65 constructed in accordance with these improvements.

Figure 2 is a plan of the instrument seen in Figure 1.

The instrument illustrated in the drawing 70 comprises, firstly, an explorer-guide-protector constituted by an end part *a* formed of solid rubber and having an olive-shaped tip and a protecting caoutchouc tube *c* fixed to the upper end of the part *a* which tube 75 encircles a central metallic guide rod *b*. The instrument comprises, secondly, a metallic olive *d*, which may be one of a series of graduated dimensions. These olives are perforated along their central axes in order 80 to enable them to be slid on to the rod *b*. For moving an olive *d* along the rod *b* a pusher device *e* is provided so that the olive *d* may be pushed along to the region of the contraction where it exercises its action in 85 a gentle and unobjectionable manner as it traverses the sheath of caoutchouc, which protects the mucus.

The explorer-guide-protector comprises three parts. (a) The explorer, properly so-called, consisting of the part *a* which is formed as a small cone of solid rubber terminated by an olive tip. The form and diameter of this part are such as to permit of entering and overcoming easily and without violence the point of spasm or constriction. (b) The guide *b* constituted by the metallic rod which is sunk into and fixed solidly in the axis of the cone of rubber *a*. This rod is of circular cross section and is 100 very smooth. Also, its length is sufficient for it to extend from the stomach to the outside of the mouth and it should possess a slight flexibility. (c) The protector *c* consists of a sheath of red caoutchouc which is 105 expandible and very smooth. This sheath is attached to the periphery of the upper part of the cone *a* and encloses the metallic rod *b* from which it is separated by a large empty space through which pass the successive dilators or olives. The caoutchouc sheath *c* is 110 not quite so long as the guide rod *b* which

should pass out from it on the outside of the mouth, so that its length should be superior to the distance between the lips and the stomach. The caoutchouc is extremely smooth interiorly and exteriorly and a little expansible but not so soft that it might be liable to be puckered or deformed by the descent of the olive.

The pusher-dilator comprises two parts, 10 (a) A metallic olive *d* constituted by a cylindrical body terminated by slender cones at its two extremities and perforated centrally for enabling it to slide on the guide rod *b*. (b) A pusher *e* which is a metal rod 15 having its extremity screwed eccentrically into the olive *d* and adapted to push the latter along the length of the guide *b* and to move it to and beyond the point of constriction. This rod may be graduated in centimetres and carries rings *f* spaced from one 20 another and engaging the guide rod *b* and so holding the rod *e* substantially in the axis of the sheath *c*. By unscrewing the olive *d* it is possible to substitute another and so to 25 substitute successively a number of olives of different dimensions each olive being mounted on the pusher in a similar manner.

I claim:—

1. An instrument for dilating organic conduits affected by constriction or spasm, comprising a smooth protective sheath of caoutchouc, a small conical solid rubber element

terminated by an olive tip fixed at the small end of said sheath, a metallic guide rod within the sheath fixed in the center of 35 the upper part of said conical solid rubber element, an olive perforated through its middle for sliding over the guide rod said olive being adapted for sliding within the sheath, an operating rod attached to the 40 olive, and guide eyes fixed to said operating rod and engaging the guide rod.

2. An instrument for dilating organic conduits affected by constriction or spasm, comprising a smooth protective tapering sheath, 45 an olive tip at the small end of said sheath, longitudinal guide means within said sheath, an olive slideable on said guide means within said sheath and adapted for dilating or expanding the latter, and a push rod detachably connected with said olive substantially as set forth.

3. An instrument for dilating organic conduits affected by constriction or spasm, comprising a smooth expansible sheath closed at 55 one end by a solid rounded tip, a rigid non-compressible olive slideable within said sheath, operating means for sliding said olive along the interior of said sheath, and guide means centrally disposed within said sheath, said operating means and said guide means having guiding engagement one with the other substantially as set forth.

Dr. LUDOVIC JULES MARIUS PLANTIER.
